US0D1038408S

(12) **United States Design Patent** (10) **Patent No.:** **US D1,038,408 S**
(45) **Date of Patent:** **** Aug. 6, 2024**

(54) **LIMB PROTECTOR**

(71) Applicants: **LA POINTIQUE INT'L Ltd.**, Seattle, WA (US); **Plus Meditech Co., Ltd.**, Tainan (TW)

(72) Inventor: **Yueh-Hua Chiang**, Taipei (TW)

(73) Assignees: **LA POINTIQUE INT'L Ltd.**, Seattle, WA (US); **Plus Meditech Co., Ltd.**, Tainan (TW)

(**) Term: **15 Years**

(21) Appl. No.: **29/784,775**

(22) Filed: **May 21, 2021**

(30) **Foreign Application Priority Data**

Nov. 24, 2020 (TW) 109306560

(57) **CLAIM**

The ornamental design for a limb protector, as shown and described.

DESCRIPTION

FIG. 1 is a perspective view of a limb protector showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed broken lines depict portions of the limb protector in which the design is embodied that form no part of the claimed design.

1 Claim, 6 Drawing Sheets
